UNITED STATES PATENT OFFICE.

CHARLES SPILKA, OF NEW YORK, N. Y.

DESIGN FOR A DISPLAY-BOX.

SPECIFICATION forming part of Design No. 26,119, dated September 29, 1896.

Application filed August 8, 1896. Serial No. 601,927. Term of patent 14 years.

To all whom it may concern:

Be it known that I, CHARLES SPILKA, a citizen of the United States, residing at New York city, in the county and State of New York, have invented and produced a new and original Design for Display-Boxes, of which the following is a specification, reference being had to the accompanying drawing, forming a part thereof, which represents a perspective view of a box embodying the features of the design.

The design consists in the lineature of the interior of the box, in which the box contains one or more dual pockets B, each set of pockets having the characteristics of a partition, and in configuration each pocket of a set is so designed that in plan view one end a is of

approximately semicircular shape, the semicircular lines meeting converging side lines a', while the converging side lines of one pocket of a set connect with the semicircular lines of the following pocket of the same set. A border b follows the marginal outline of each set of pockets. A minor feature of the design consists in salient figures b', located at the contracted ends of the pockets.

I claim—

The design for a box herein shown and described.

CHARLES SPILKA.
